INSEAM SHOE SEWING MACHINE

Alfred R. Morrill, Beverly, Mass., assignor to
United Shoe Machinery Corporation, Paterson,
N. J., a Corporation of New Jersey

Application July 25, 1927. Serial No. 208,116

19 Claims. (Cl. 112—35)

The present invention relates to inseam shoe sewing machines and is herein disclosed as embodied in a machine for sewing the upper to the sole of a turn shoe, the operating instruments of which include a curved hook needle, an awl or feed point cooperating therewith, a looper, a thread finger, a channel guide, and a take-up.

The object of the invention is to produce a novel and improved machine of this type which will have a novel and advantageous arrangement of the operating elements, will operate more accurately and efficiently than machines previously produced, and may be more readily controlled by the operator to run at a fast or slow speed and to stop with the needle retracted from the work.

The several features of the invention consist in the devices, combinations and arrangement of parts hereinafter described and claimed, and together with the advantages to be obtained thereby should be readily understood by one skilled in the art from the following description taken in connection with the accompanying drawings.

In the drawings which illustrate the preferred embodiment of the invention in a turn sewing machine, Fig. 1 is a view in side elevation of the whole machine; Fig. 2 is a plan view of the base of the machine taken on the line 2—2 of Fig. 1; Fig. 3 is a sectional view in side elevation of the base taken on the line 3—3 of Fig. 2; Fig. 4 is a detail view partly in section taken on the line 4—4 of Fig. 6 of the knee control mechanism for operating the machine at low speed, the parts being shown in position for the full speed operation; Fig. 5 is a view similar to Fig. 4 with the parts in position to operate the machine at low speed; Fig. 6 is a plan view of the parts shown in Figs. 4 and 5 taken on the line 6—6 of Fig. 1; Fig. 7 is an enlarged view in front elevation of the head of the machine; Fig. 8 is a plan view of the head of the machine; Fig. 9 is a view of the head of the machine in left elevation; Fig. 10 is a view in right side elevation partly in section illustrating particularly certain of the operating instruments and actuating mechanism; Fig. 11 is a detail plan view of a portion of the mechanism for operating the thread finger; Fig. 12 is a view in right side elevation of the head of the machine; Fig. 13 is a sectional plan view of the head of the machine taken on the line 13—13 of Fig. 12; Fig. 14 is a vertical sectional view taken on the line 14—14 of Fig. 12; Fig. 15 is a detail sectional

view of the two speed and reversing switch taken on the line 15—15 of Fig. 14; Fig. 16 is a detail view on the line 16—16 of Fig. 14 illustrating particularly the mechanism for starting and stopping the machine, the parts being shown in rest position; Fig. 17 is a detail sectional view taken on the line 17—17 of Fig. 16; Figs. 18, 19 and 20 are views similar to Fig. 16 illustrating different positions of the starting and stopping mechanism, the parts being shown in low, high and reverse positions respectively; Fig. 21 is a detail view in left side elevation illustrating particularly the switch cam mechanism for operating the thread arm and for causing the looper to avoid threading the needle at the last stitch upon stopping the machine; Fig. 22 is a detail view of the take-up lever and its actuating cam; Fig. 23 is a view in right elevation of the mechanism shown in Fig. 21 with the parts in the position they assume immediately after the stopping mechanism has been thrown into operation; Fig. 24 is a detail sectional plan view of the stitch forming devices in the position illustrated by Fig. 23; Fig. 25 is a view in right elevation of the switch cam mechanism illustrating the parts in rest position as in Fig. 21 after the machine has been stopped; Fig. 26 is a view similar to Fig. 23 illustrating the positions of the parts immediately after starting the machine; Fig. 27 is a detail view in right elevation of certain of the operating elements of the machine, the parts being shown in rest position; Fig. 28 is a view in front elevation of the parts illustrated in Fig. 27; Fig. 29 is a detail sectional plan view illustrating the operating elements in the position shown in Fig. 27; Figs. 30 and 31 are corresponding views in side elevation and plan illustrating the position of the operating elements at a point in the formation of the first stitch after the machine is started; Figs. 32 and 33 are views similar to Figs. 30 and 31 showing the position of the elements at the end of the loop drawing stroke of the needle in the formation of the first stitch; Figs. 34 and 35 are similar views illustrating the position of the parts during the feeding of the work by the awl or feed point; Figs. 36 and 37 are similar views illustrating the position of the parts at the end of the advancing stroke of the needle and during the threading of the needle; and Figs. 38 and 39 are similar views illustrating the position of the parts at the end of the loop drawing stroke of the needle during the formation of the second and succeeding stitches.

The shoe machine illustrated in the drawings is adapted for sewing the upper to the sole of a

turn shoe and is provided with the usual operating elements of a chain stitch turn sewing machine comprising a curved hook needle, a curved awl cooperating therewith, a looper, a thread arm, a take-up, a back gage, a channel guide and a back rest. These elements are arranged and actuated to secure a continuous and even feed of the work, the needle and channel guide to this end being mounted on one slide to move together in the line of feed, while the awl and back gage are similarly mounted on a second slide. In order to facilitate the handling of the work by the operator, especially when operating on the toe of the shoe, and also to secure a more convenient arrangement of parts, the awl is arranged to pierce the work from the outside, that is, the side on which the upper is located being positioned on the same side of the work as the needle. The machine is driven by means of a motor which is adapted to run at either of two speeds, and is controlled by the operator through a two speed starting and stopping switch which operates to stop the machine with the needle retracted from the work. The machine is also provided with means for preventing the threading of the needle during the last stitch forming cycle and for cutting and holding the thread as the machine stops and with simplified and improved means for operating the various parts.

Referring more specifically to the drawings, the casing, which forms the head of the machine and houses the sewing mechanism and the electric motor by which it is driven, is indicated at 42 and is adjustably supported on a column or base 44. The head 42 is hinged to the base at 45 to permit the head readily to be swung forward to give access to the motor which is located in the lower portion of the head. The operating elements carried in the head of the machine, as shown in Figs. 10 and 12, include a curved hook needle indicated at 46, an awl 43, a looper 50, a thread finger 52, a channel guide 54, a back gage 56, and a take-up 58. These elements are actuated from a main cam shaft 60 mounted in the head of the machine, through mechanism hereafter described, which cam shaft is driven by the electric motor which is permanently connected to the cam shaft through a gear 62 on the cam shaft and a worm gear 64 on the vertical driving shaft 66.

A starting and stopping mechanism is provided which is treadle controlled by the operator and acts automatically when thrown into operation to stop the machine with the needle withdrawn from the work. This mechanism comprises a two speed starting and stopping switch for the motor and mechanism which is actuated by the foot treadle to throw the switch into low speed position and thereafter acts in timed relation to the rotation of the cam shaft to shift the switch to the reverse position to stop the machine with the needle removed from the work.

The two speed starting and stopping switch for the motor is mounted concentrically with the main cam shaft 60 in a casing 68 which, for convenience of assembling and repair, is pivotally mounted at 70 on the head of the machine and held in position by means of a screw 72. When the switch casing 68 is released and swung back out of the way, the plate 69 which is screwed to the head casing 42 may be readily removed to give access to the cam shaft. The switch is controlled partly from the starting treadle of the machine and partly from the main cam shaft 60. Referring to Figs. 14, 15 and 16, the switch

blades as indicated at 74, are mounted upon a rotatable frame 76 and are arranged to cooperate with spring contact plates 78 rigidly mounted on the casing 68. The blades 74 are suitably cross connected and the contact plates 78 are connected to the lead-in wires 80 of the motor which enter the switch casing 68 through the pivot 70. The blades and contact plates of the switch are so arranged and connected that in the different positions of the switch the circuits of the motor may be open or they may be connected to cause the motor to run at a high or low speed or to reverse its direction of rotation. The switch may be said, therefore, to be movable to high, low, reverse and off positions.

The rotatable frame 76 on which the blades are mounted is loosely sleeved on a fixed stud 82 in the casing 68 and is provided at one end with a clutch face 84 which is held yieldingly in engagement with a corresponding surface 86 on the abutting end of the switch actuating shaft 88 by means of a spring 89 coiled about the fixed stud 82 within the rotatable frame 76.

The mechanism for actuating the switch actuating shaft 88 and thus for positioning the starting and stopping switch, comprises (see Figs. 13, 14 and 16-20, inclusive) a control lever 90 loosely mounted on a shaft 92 and provided with a gear segment 93 adapted at all times to engage a pinion 94 formed on the shaft 88. A plunger 95 mounted in a casing 96 in the machine frame is forced by means of a heavy spring 98 into contact with the control lever 90 and tends to swing it about the pivot shaft 92 and acting through the actuating shaft 88 to throw the starting and stopping switch into low speed position. The abutment 100 on the plunger which engages the end of the casing 96 prevents movement of the plunger beyond this point. On the upper portion of the control lever 90 is mounted a spring pressed bolt 101 formed at its outer end as a cam follower or roll 102 which in the rest position of the mechanism is illustrated in Fig. 16 engages a cam groove 104 formed in the face of the cam disk 282 secured to the main cam shaft 60 and so locks the control lever 90 against movement under the pressure of the spring 98. There is also loosely mounted on the pivot shaft 92 a lever 108 which is controlled through intermediate connections hereinafter to be described from the foot treadle 132 of the machine. This lever is provided with a cam surface 112 which is adapted to engage an arm 114 of a yoke 116 pivotally mounted at 118 on the control lever 90 to engage a groove in the bolt 101.

When the treadle is depressed in starting the machine, the lever 108 is rotated in a counter clockwise direction from the position illustrated in Fig. 16, to bring the cam surface 112 into contact with the projecting arm 114 of the yoke 116 which acts in turn to withdraw the cam roll 102 from engagement with the cam groove 104 thus permitting the control lever 90 to swing about its pivot under the pressure of the heavy spring 98 into low speed position as previously explained. The control lever is held in low speed position in contact with the plunger 95 by means of a tension spring 120 which is connected between a lever arm 122 formed on the lever 108 and a point 124 on the control lever 90. The further movement of the foot treadle to its lowest position causes the lever 108 to be rotated still further in a counter clockwise direction about its pivot, thus swinging the lever arm 122 and the tension spring 120 past center to swing the control lever 90 to

its furthest limit and to rotate the switch to high speed position.

Mechanism is provided for bringing the machine to a stop in a predetermined angular position with the needle retracted from the work independently of whether the machine is operating at high or low speed. When the treadle is released during high speed operation, the switch is first thrown into low speed position where it is held for nearly one complete revolution of the cam shaft and is then thrown into reverse at a predetermined angular position of the cam shaft. The machine will thus be operating at low speed when the switch is thrown to reverse, and the inertia to be overcome by the reversing torque of the motor will always be the same and the machine will be stopped at the same point with the needle withdrawn from the work.

In stopping the machine when the treadle is released, the lever 108 is swung downward in a clockwise direction from the position illustrated in Fig. 19. The lever arm 122 with the tension spring 120 is again moved past the center position causing the control lever 90 to swing back again about its pivot to low speed position (see Fig. 18), where it is held by contact with the spring pressed plunger 95. In this position of the parts, as illustrated particularly in Fig. 18, with the foot treadle partially raised and the control lever 90 in low speed position, the cam roll 102 is still held in retracted position out of contact with the cam disk 106 by the engagement of the cam surface 112 on the lever 108. When the treadle is entirely released permitting the lever 108 to return to the rest position illustrated in Fig. 16, the cam roll 102 is released and is pressed endwise against the face of the cam disk 282 until the cam disk 282 reaches a position in which the cam roll can enter the extreme outer portion of the cam groove 104. Continued rotation of the cam disk causes the control lever 90 to be moved to its extreme left position against the pressure of the spring pressed plunger 95, as illustrated by Fig. 20, corresponding to the reverse position of the switch. The contour of the cam groove 104 is such as to permit the cam shaft 60 to make nearly a complete revolution with the switch set at low speed position before the switch is thrown to reverse at a predetermined angular position of the cam shaft. The control lever 90 is held in reverse position until the machine is brought to a complete stop and starts to reverse under the influence of the reversing torque imparted to the motor, by the engagement of an abutment 126 with a catch 128 formed on a ring 130 surrounding the cam shaft and connected therewith by an overrunning clutch arrangement of ordinary construction. During the normal operation of the machine, the catch 128 is held in position by means of a spring pressed detent lever 132 mounted on the machine frame. When the machine starts to reverse, the ring 130 will be clutched to the main cam shaft 60 and will rotate therewith in a counter clockwise direction as indicated in Fig. 20 to release the control lever 90 which will then be returned by the pressure of the spring pressed plunger 95 as far as rest position where it is held by the engagement of the cam roll 102 with the outer wall of the groove 104. The starting and stopping treadle of the machine is indicated at 132 pivotally mounted at 134 on the machine frame and bears at its rear end against the lower end of a vertical rod 136 which forms one of the connections to the lever 108 for operating the starting and stopping switch. The

vertical rod 136 is normally held in a depressed position with the foot treadle raised by means of a compression spring 138 coiled about the rod between a collar 140 on the rod and a bracket 142 through which the rod slides. A sleeve 144 is formed at the upper end of the rod 136 to receive the lower end of a rod 146 which is threaded for lengthwise adjustment to an elongated nut or sleeve 148 adapted to fit within the sleeve 144 and connected thereto as will be described.

Mechanism is provided for enabling the operator to reduce the machine to low speed whenever it is desired to do so independently of the foot treadle and without throwing the stopping mechanism into operation. This mechanism comprises a knee treadle 149 mounted upon a rod 150 which is loosely fitted to move longitudinally in the bracket 142 and is normally held in an advanced position by means of a compression spring 152 coiled about the rod between a collar 154 and the bracket 142. The movement of the rod 150 is limited in one direction by the engagement of a collar 156 with one arm 150 of the bracket and in the other direction by the engagement of a collar 160 with another arm 162 of the bracket. A link 164 is pivotally secured at one end to the collar 156 on the rod 150 and at the other end to the central pivot of two toggle levers 168 and 170 which are connected respectively at their free ends to the nut 148 on the rod 146 and the sleeve 144 on the rod 136. The toggle is held normally in straightened position by the pressure of the spring 152 on the knee treadle rod 150 to hold the rods 136 and 146 rigidly in position with relation to each other when they are raised or lowered by the action of the foot treadle in starting and stopping the machine. When, however, it is desired to operate the machine at low speed, the knee treadle 149 is pressed inwardly by the operator breaking the toggle and depressing the rod 146 part way to bring the lever 108 exactly to low speed position.

The connections through which the lever 108 in the head of the machine is actuated from the rod 146 in the base are arranged concentrically with the hinge 45 to permit the head 42 of the machine to tip about its pivot without injury to the parts. One arm of the lever 108 is connected to the upper end of a vertical rod 174 which is connected at its lower end to a lever arm 176 formed on a sleeve 178 surrounding the hinge 45. A second lever arm 180 is formed on the sleeve 178 to engage the upper end of the vertical rod 146 and is held yieldingly in engagement therewith by means of a spring 182 coiled about the hinge 45.

In order that the machine may be readily adjusted to the height of the operator, the head 42 is mounted on a tubular support 184 which fits tightly into the upper end of the base 44. A vertical shaft 186 is rotatably mounted in a journal 188 formed in the support 184 and is held against endwise movement relatively thereto by means of a bearing block 190 formed on the shaft which is adapted to sustain the weight of the support 184 and the head 42. The shaft 186 at its lower end is threaded into a stationary nut 192 mounted in the base 44 and its upper end is provided with a pinion 194 adapted to engage with a worm gear 196 on a hand operated cross shaft 198 so that the shaft 186 may be readily rotated to raise or lower the head of the machine. The rod 146 through which the starting and stopping switch is controlled also carries a pinion 200 which meshes with the pinion 194 so that

the rod 146 is rotated to adjust itself automatically as the head of the machine is raised or lowered.

The general construction and mode of operation of the operating elements in the head of the machine are similar in many respects to those disclosed in the inventor's pending application for a shoe machine, Serial No. 114,441, filed June 8, 1926. The work engaging parts of the sewing mechanism are arranged on the slides to feed the shoe continuously through the machine and the thread handling devices operate to form a chain stitch the chain of which is laid on the upper of the shoe. The needle is clamped to a needle carrier 204 which is mounted to oscillate and also to move in the line of feed to assist in feeding the work. The needle carrier 204 is formed integrally with a sleeve 206 on one side which surrounds a shaft 208 and on the other side is formed integrally with a shaft 210 to which is sleeved the supporting hub 212 for the thread finger and channel guide. Two sleeves 214 and 216 cap the shafts 208 and 210 at each end of the slide. To oscillate the needle, the carrier 204 is connected by means of a link 218 with one end of a cam actuated lever 220 which is loosely mounted on a shaft 222 and carries at its other end a cam roll 224 adapted to engage in a cam groove formed on the face of the gear 62. The needle carrier also has a lateral movement to impart work feeding and return movements to the needle and accordingly a universal joint is provided at each end of the connecting link 218. Movements are imparted to the needle carrier to give the lateral feeding and return movements to the needle by means of two levers 230 and 232 mounted respectively on pivot shafts 234 and 236, (see Fig. 10) and engaging at their forward ends slots 238 formed in the ends of the sleeves 214 and 216 of the needle slide. The levers 230 and 232 are connected by a link 240 and the lever 232 is provided with a rearward extension carrying a roll engaging a cam in the periphery of the cam disk 242 on the cam shaft 60. The needle guide 244 (see Figs. 10, 12, 27 and 28) is mounted on a block 246 which is rigidly mounted on the shaft 208 and operates in a slot 248 formed in the needle carrier 204. The shaft 208 is rotated to oscillate the needle guide in timed relation to the movement of the needle by means of a gear segment 250 formed on the shaft 208 which engages with a rack 252 formed on the forward end of the rod 254, the rear end of which is connected to one end of the bell crank lever 256 loosely mounted on the shaft 222. The free end of the bell crank carries a roll 258 adapted to engage a cam on the face of the cam disk 242 on the cam shaft 60. The channel guide 54 is rigidly mounted on the hub 212 of the thread finger carrier 262 so that the movements imparted to the upper portion of the thread finger carrier will cause the channel guide to be moved towards and away from the work. The carrier is oscillated during each cycle of operations of the machine to impart the required movements to the channel guide by means of a cam lever 264 which is pivoted on the shaft 222. The lever is connected at one end to the carrier 262 by a link 266 and at its other end carries a cam roll 268 adapted to ride in a cam groove in the gear 62 on the cam shaft 60. Since the thread finger carrier is moved laterally with the needle during the work feeding and return movements of the needle slide, a universal

joint is provided at each end of the connecting link 266.

The thread finger 52 of the illustrated machine cooperates with the looper in supplying thread to the needle during each stitch forming cycle, and like the thread finger of the machine disclosed in application Serial No. 114,441, is also utilized at the conclusion of the sewing operation as a part of a mechanism for severing and holding the thread between the looper and the work. The thread finger is formed on the lower end of a rock shaft 272 mounted in the thread finger carrier 262. The shaft 272 is rocked to cause the thread finger to draw off the requisite amount of thread for each stitch by means of a cam lever 274 secured to a loose sleeve 276 on the shaft 222 and provided at one end with a cam roll 278 adapted to ride normally during the operation of the machine in a groove 280 in a cam disk 282 mounted on the shaft 60. The roll 278 is held yieldingly against the inner surface of the cam groove 280 by means of a tension spring 284 stretched between a point on the machine frame and an arm 286 formed on the under side of the sleeve 276. A link 288 provided at each end with universal joints connects the free end of the cam lever 274 with an arm 290 formed on the upper end of the rock shaft 272.

As has been stated, the thread finger carrier 262 is mounted to move laterally in the line of feed with the needle carrier. The thread finger thus maintains its proper position with relation to the needle during the lateral movements of the needle to and fro in the line of feed and operates to handle the thread to the best advantage at all points in the stitch forming cycle. To further improve the operation of the thread finger, the rock shaft 272 and the thread finger are so arranged that the thread finger extends across the line of feed and has a thread drawing movement substantially in the line of feed across the plane of the needle and in the opposite direction to the feed of the work. With this arrangement and mode of operation of the thread finger, the proper length of thread will be drawn out by the thread finger regardless of variations in the length of the stitch caused by the manipulation of the shoe by the operator or for any other reason.

The mechanism for cutting off and holding the thread at the end of each sewing operation and for holding the thread during the first stitch of the following operation comprises a thread gripper lever 292 mounted on the lower end of the thread finger carrier 262 and forced yieldingly in a direction to grip the thread against the thread finger by means of a spring 294 coiled in a recess in the rock shaft 272 within the carrier 262. An abutment 296 is formed on the carrier to engage the thread gripper lever 292 and limits the movement of the lever 292 under the pressure of the spring 294. A thread cutter 298 is pivotally mounted on the under side of the thread finger 52 being held normally out of operation against a detent pin 300 by means of a small spring 302. However, when the thread gripper 292 is brought into contact with the thread finger to grip the thread, the lower edge 304 of the gripper will come into contact with the free end of the thread cutter 298 and cause it to swing about its pivot against the pressure of the spring 302 to cut the thread. The movements imparted to the thread finger by the cam groove 280 during normal operation are merely sufficient to measure off the thread between the needle and the looper during each cy-

cle of operations of the sewing devices and do not bring the thread finger into contact with the thread gripper lever 292.

At the end of the sewing operation during the last stitch forming cycle as the machine is being brought to a stop, the thread finger is given a wide swinging movement which brings it into contact with the spring pressed thread gripper lever 292 to sever and hold the thread.

10 thread finger is held in contact with the thread gripper lever also during the first stitch of the next sewing operation to insure that the thread is properly held and supplied to the work. The mechanism for changing the position of the

15 thread finger to cooperate with the thread gripper lever 292 to cut and hold the thread comprises an auxiliary cam groove 310 formed on the face of the cam disk 282 adjacent to the groove 280 and a switch cam 312 (see Figs. 21,

20 23, 25 and 26) pivotally mounted at 314 on the face of the disk 282. During the last stitch forming cycle, the lever 274 carrying the cam roll 278 is depressed against the pressure of the spring 284 causing the cam roll to pass into the

25 outer groove 310 as shown in Fig. 23, which swings the thread finger 52 about its pivot into contact with the spring pressed thread gripper lever 292. The cam roll 278 makes nearly a whole revolution in the cam groove 310 before the machine

30 comes to rest in the position illustrated in Fig. 25. When the machine is started, the cam roll 278 passes under the switch cam 312 so that the cam roll is retained in the outside groove during one revolution to insure that the thread end

35 is properly held and supplied to the work on the first stitch. The position of the switch cam, however, is altered by the passage of the roll under it so that during the second revolution of the cam shaft the roll is again caused to enter

40 the inside groove 280 to release the thread end and permit the normal operation of the thread finger.

The lever 274 carrying the cam roll 278 is depressed in timed relation to the rotation of the

45 cam shaft 60 to cause the roll to pass into the outer groove through the passageway provided by the switch cam by means of connections from the starting and stopping mechanism which are rendered active in stopping the machine.

50 These connections comprise a spring plunger or detent 316 mounted on a lever arm 318 on the sleeve or hub 276 of the lever 274 and an arm 320 adapted to cooperate therewith formed on the switch control lever 90.

55 The end of the detent 316 and the lever arm 318 are shaped so that when the lever 90 is rotated in the opposite direction in starting the machine, the spring detent 316 will merely be forced back against the pressure of its spring to permit the lever arm 320 to pass.

60 The awl 48 and the back gage 56 are mounted on a carrier 322 which slides in the machine frame to impart a feeding motion to these elements while in contact with the work. The carrier 322 is pivotally mounted by means of

70 the stub shafts 324 integral therewith which are journaled in bearings in the frame and are adapted for lengthwise movement in the direction of feed of the work. The carrier is moved back and forth in the line of feed by two levers 326 and 328 which are secured respectively to

sleeves 330 and 332 on the stub shafts 324 and 326 and are secured to move together by a connecting link 338. The levers engage at their free ends in recesses formed in the stub shafts 324, and the lever 326 is provided with a rearwardly extending arm which carries a cam roll 340 engaging with a cam formed on the periphery of a cam disk on the main cam shaft 60.

80 The rotary movements are imparted to the carrier 322 to move the awl and the back gage 85 towards and away from the work by means of a lever 344 loosely sleeved to the shaft 222 and provided at one end with a cam roll 346 which engages a cam groove in the face of the gear 62 on the main cam shaft 60. The lever 344 is also connected to the awl carrier 322 by means of a link 348 which is provided at each end with universal joints to allow the transverse feeding movement of the carrier.

90 The back gage 56 is yieldingly mounted in the carrier 322 in a curved guideway and is held normally in forward position by means of a compression spring 352 mounted in a recess in the carrier. When the awl is advanced to engage the work, the back gage will come yieldingly into 95 contact with the shoe where it will be held by the pressure of the spring 352 until the awl is withdrawn.

95 The looper mechanism of the illustrated machine is similar to the looper mechanism disclosed in the applicant's prior application, Serial No. 114,441, and comprises a tubular shaped member 50 which is pivotally mounted at its upper end by means of a universal joint 354 to a support 356 which is in turn pivotally mounted 105 at 358 on the machine frame. The looper is actuated to carry its lower end around the needle so as to thread the hook of the needle by means of two cam actuated bell crank levers 360 and a triangularly shaped lever or link 362 connected 110 to the bell crank levers and to the looper lever by universal joints as in the construction disclosed in the above mentioned application.

105 To prevent the needle from being threaded during the last cycle of operations of the sewing mechanism, the illustrated machine is provided with means for moving the support 356 so as to raise the looper in a direction substantially lengthwise of the needle. With the present construction, a novel and improved means is provided to this end which comprises a hook shaped projection 364 on the link 288 of the thread finger actuating mechanism which is normally held out of engagement with a corresponding abutment 366 formed on the hub of the support 356. However, when the thread finger is moved into contact with the thread gripper lever 292 at the end of the sewing operation with a correspondingly large backward movement of the link 288, the hook 364 is brought into contact with the abutment 130 to rotate the support 356 about its pivot and raise the looper.

135 From an inspection of Figs. 23 and 26, it will be seen that the portion of the cam groove 310 with which the roll 278 on the lever 274 engages 140 while the looper is carrying the thread around the needle is enlarged so that during the last stitch forming cycle while the machine is being stopped, the lever 274 can be held in a position as indicated in Fig. 23 which raises the looper above 145 the end of the needle so that the needle will not be threaded. During the first stitch forming cycle at the beginning of the next sewing operation, however, the lever 274 has been released by the switch controlling lever 90 of the stop mechanism 150

and can assume the position indicated in Fig. 26 in which position the looper has been lowered so that during the first stitch forming cycle the needle will be properly threaded.

5. A bunter or back support is provided for the work which comprises a roll 370 loosely mounted to rotate on the curved support 372 which is pivotally mounted at 374 on the machine frame and is held yieldingly in position by means of a spring 376.

10. The thread coming from the thread supply passes through the wax pot 378 and the stripers 380 to a thread tension of ordinary design indicated at 382 and from there over a roll 384 mounted on the thread take-up lever 386 to the looper 50.

15. As is usual in chain stitch shoe sewing machines provided with a take-up, the take-up of the illustrated machine exerts a stitch setting strain on the seam while the needle is in the work. In machines having this mode of operation, it is desirable that the needle as it reaches the limit of its backward stroke exert a pull on the thread against a yielding resistance. To secure such a result under all conditions of sewing and to render the action of all of the thread handling devices certain, reliable and uniform, the illustrated machine is provided with means for yieldingly supporting the take-up against the strain of the needle as the needle reaches the limit of its backward stroke. The take-up lever 386 is pivotally mounted at 388 on the machine frame and is positively actuated to exert a stitch setting strain on the seam while the needle is in the work by a cam groove 390 formed in the face of the cam 242 on the cam shaft 60 which cam groove engages a roll 392 mounted on the rear end of the take-up lever. A spring 394 is coiled about the pivot 388 of the take-up lever and tends to hold the cam roll 392 against the side of the cam groove 390. In order to permit the take-up to be yieldingly instead of positively supported as the needle reaches the limit of the backward stroke, the groove 390 is widened at the proper point in its length as illustrated in Fig. 22 to permit the take-up lever to yield slightly under the pull on the thread exerted by the needle.

20. The driving and stopping mechanism of the machine forms the subject-matter of a divisional application, Ser. No. 425,342, filed February 1, 1930. 25. The novel features of construction embodied in the column of the machine form the subject-matter of divisional application Serial No. 648,074, filed December 20, 1932.

30. The invention having been described, what is claimed is:

1. A chain stitch shoe sewing machine having, in combination, work feeding and stitch forming devices adapted to maintain a continuous feed of the work including a hook needle, an awl, a looper, an awl slide, a needle slide, a thread holding gripper mounted on the needle slide, and a thread finger mounted on the needle slide movable into engagement with said gripper to hold the thread.

35. 2. A chain stitch shoe sewing machine having, in combination, a hook needle, a looper, a spring pressed take-up acting to exert a stitch setting strain on the thread while the needle is in the work, a cam follower operatively connected with the take-up, and a cam groove cooperating therewith to actuate the take-up provided with a widened portion to permit the take-up to yield against the pressure of its spring during the retracting movement of the needle.

40. 3. A sewing machine having, in combination, stitch forming devices including a spring pressed

take-up lever, a cam follower operatively connected with the take-up lever, a cam groove cooperating therewith to actuate the take-up lever and provided with a widened portion to permit the take-up lever to yield against the pressure of its 80 spring.

4. An inseam shoe sewing machine having, in combination, work feeding and stitch forming devices, including a curved hook needle, an awl arranged to operate from the outside of the work, 85 a channel guide, a back gage, a slide on which the needle and channel guide are mounted movable in the line of feed, and a separate slide on which the awl and back gage are mounted movable in the line of feed.

90. 5. An inseam shoe sewing machine having, in combination, work feeding and stitch forming devices acting to maintain a continuous feed of the work, including a curved hook needle, an awl, a back gage, a channel guide, a slide on which the needle and channel guide are carried, and a separate slide on which the awl and back gage are carried.

95. 6. An inseam shoe sewing machine having, in combination, work feeding and stitch forming devices acting to maintain a continuous feed of the work, including a curved hook needle, an awl, a back gage, a channel guide, a looper, a thread finger, a slide on which the needle, channel guide and thread finger are carried, and a 100 separate slide on which the awl and back gage are carried.

105. 7. An inseam shoe sewing machine having, in combination, work feeding and stitch forming devices, including a hook needle, an awl arranged 110 to operate from the outside of the work, an awl carrier movable towards and from the work, and a back gage yieldingly mounted on the awl carrier.

110. 8. An inseam shoe sewing machine having, in combination, work feeding and stitch forming devices adapted to maintain a continuous feed of work, including a curved hook needle, a channel guide, a slide on which the needle and channel 115 guide are mounted, an awl, an awl carrier movable towards and from the work adapted to slide in the line of feed, and a back gage yieldingly mounted on the awl carrier.

120. 9. An inseam shoe sewing machine having, in combination, work feeding and stitch forming devices, including a needle, a channel guide, an awl, an awl carrier movable towards and from the work, and a back gage yieldingly mounted on the awl carrier, and mechanism for reciprocating them in the line of feed timed to back feed the 125 needle and channel guide during the forward feed of the awl carrier and to back feed the awl carrier during the forward feed of the needle and channel guide.

130. 10. An inseam shoe sewing machine having, in combination, stitch forming and work guiding mechanism, including a needle and a channel guide adapted to oscillate towards and away from the work in timed relation to the oscillation 135 of the needle, a slide on which the needle and channel guide are mounted movable in the line of feed, a back gage, and a separate slide for the back gage movable in the line of feed.

140. 11. An inseam shoe sewing machine having, in combination, stitch forming and work feeding devices adapted to maintain a continuous feed of the work comprising a needle, a back gage, and a channel guide adapted to oscillate toward and away from the work in timed relation to the 145 oscillation of the needle, a slide on which the 150

needle and channel guide are carried movable in the line of feed, and a separate slide for the back gage movable in the line of feed.

12. An inseam shoe sewing machine having, in combination, stitch forming devices, including a hook needle, a looper, a thread finger, a thread holding gripper mechanism for moving the thread finger into engagement with said gripper during the last stitch to engage and hold the thread, and connections from said mechanism to the looper for moving the looper to misloop the needle.

13. An inseam shoe sewing machine having, in combination, stitch forming devices including a curved hook needle, a looper, a thread finger, a thread holding gripper, thread severing devices, mechanism for moving the thread finger to clamp the thread against said gripper and to cause the severing devices to cut the thread during the last stitch, and connections from said mechanism to the looper for moving the looper to misloop the needle during the last stitch.

14. An inseam shoe sewing machine having, in combination, stitch forming devices including a curved hook needle, a thread finger having a movement substantially in the line of feed, a thread gripper lever held normally out of engagement with the thread finger, a feed slide on which the needle, the thread finger, and the thread gripper lever are mounted movable in the line of feed, and means rendered active in stopping the machine to impart to the thread finger an extraordinary movement to engage the thread gripper lever and hold the thread.

15. A machine for operating upon shoes having, in combination, devices for operating upon a shoe, actuating mechanism therefor including a cam follower, a cam provided with two cam paths to engage the follower, a switch cam, a motor from which the machine is driven, a control switch therefor, a switch control member, a cam for actuating said member, and means thrown into operation in stopping the machine for causing the cam to operate the switch control member to render the switch operative and direct the follower from one cam path into the other.

16. A shoe sewing machine having, in combination, stitch forming devices, including a hook

needle, a looper, mechanism for swinging the looper to move its thread carrying end about the needle, a motor from which the machine is driven, a control switch therefor, a switch control member, a cam for actuating said member, and mechanism rendered active by the movement of said member to move the looper to prevent laying the thread in the hook of the needle during a cycle of operations of the machine.

17. A shoe sewing machine having, in combination, stitch forming devices including a hook needle, a looper, mechanism for swinging the looper to move its thread carrying end about the needle, a cam follower, a cam provided with two cam paths to engage the follower, a switch cam, a motor from which the machine is driven, a switch control member, a cam for actuating said member, and mechanism rendered active by the movement of said member in directing the follower from one path to the other to move the looper to prevent laying the thread in the hook of the needle during a cycle of operations of the machine.

18. An inseam shoe sewing machine having, in combination, stitch forming devices including a hook needle, a looper, mechanism for swinging the looper to move its thread carrying end about the needle, a cam follower, connections from the cam follower ordinarily ineffective to move the looper, a cam to engage the follower, spring means for causing the follower normally to bear against the inner side of its cam, and mechanism rendered active in stopping the machine to cause the follower to ride on the outer edge of its cam and move the looper to misloop the needle.

19. An inseam shoe sewing machine having, in combination, work feeding and stitch-forming devices including a needle, a channel guide, an awl arranged to operate from the outside of the work, and a back gage, mechanism for reciprocating them in the line of feed timed to back feed the needle and channel guide during the feed of the awl and back gage and to back feed the awl and back gage during the forward feed of the needle and channel guide.

CERTIFICATE OF CORRECTION.

Patent No. 1,920,998.

August 8, 1933.

ALFRED R. MORRILL.

It is hereby certified that error appears in the printed specification of the above numbered patent requiring correction as follows: Page 1, line 58, after "view" insert taken; page 3, line 98, for the reference numeral "150" read 158; page 6, line 81, claim 3, after "spring" insert the words during the retracting movement of the needle; and that the said Letters Patent should be read with these corrections therein that the same may conform to the record of the case in the Patent Office.

Signed and sealed this 14th day of November, A. D. 1933.

F. M. Hopkins

(Seal)

Acting Commissioner of Patents.
